Application March 3, 1942, Serial No. 433,219

19 Claims. (CL 179—171.5)

The present invention relates to phase-modulation systems and, particularly, to such systems suitable for use in phase-modulation carrier-wave transmitters.

In frequency-modulation carrier-wave transmitters, a signal to be transmitted is applied to a modulator stage of the transmitter so to modulate a carrier wave thereof that the frequency of the radiated carrier wave is varied from instant to instant in accordance with the amplitude of the modulation signal. In one form of prior art transmitter of this nature, the modulator stage phase modulates a relatively low-frequency carrier wave in accordance with a modified modulation signal obtained by translating the original modulation signal through an integrating network. The resultant modulated carrier wave is identical to a carrier wave frequency-modulated with the original modulation signal and is changed to a relatively high-frequency modulated carrier wave, to obtain the desired wide range of frequency deviation, by the method of frequency multiplication, the latter wave being thereupon suitable for radiation by the transmitter.

In a particular form of the prior art transmitter arrangement described, the phase-modulator stage comprises two carrier-wave translating channels having common input and output circuits. A relatively low-frequency carrier wave is applied to the input circuit of the modulator stage and is directly translated through a 90-degree phase-shifting network to the output circuit of the stage. The other translating channel includes a balanced modulator having one input circuit to which the carrier wave is applied and another input circuit to which the modified or integrated modulation signal is applied. The balanced modulator is so arranged that there are developed in its output circuit only amplitude-modulation sidebands, the carrier-wave component being suppressed by the action of the modulator. The sideband components are added to the 90-degree phase-shifted carrier wave in the output circuit of the modulation stage to develop in this output circuit a carrier wave which may be considered as being phase-modulated in accordance with a distorted modulation signal or frequency-modulated in accordance with the original modulation signal. This modulated carrier wave is then applied to suitable frequency-multiplier stages of the transmitter which increase the range of frequency deviation of the carrier wave to provide a relatively high-frequency

frequency-modulated carrier wave suitable for radiation by the transmitter. This arrangement has the disadvantage that only approximate linearity of phase modulation can be obtained and this only when the maximum degree of phase modulation is of the order of plus or minus one-half radian or less. This type of phase-modulation system also requires that the carrier wave applied to the modulator stage have a relatively low frequency. There is, consequently, the further disadvantage with this system that it requires an unnecessarily large number of frequency-multiplier stages by which the low-frequency modulated carrier wave may be changed to the high-frequency carrier wave required for radiation by the transmitter. This greatly and undesirably adds to the complexity and initial cost of the transmitter and to the operating and maintenance costs thereof.

It is an object of the present invention, therefore, to provide a new and improved phase-modulation system which avoids one or more of the disadvantages and limitations of the prior art systems of this nature.

It is an additional object of the invention to provide a phase-modulation system in which the linearity of phase modulation is limited only by the degree of linearity which can be attained in the wave form of saw-tooth oscillations used in the system for phase-modulation control and, thus, one characterized by a high degree of linearity of phase modulation.

It is a further object of the invention to provide a phase-modulation system particularly suitable for use in a frequency-modulation transmitter in which the degree of frequency multiplication of the modulated carrier wave necessary to obtain a high-frequency frequency-modulated carrier wave is greatly reduced, thereby to effect a material simplification of the transmitter arrangement with consequent reduction of initial cost and operating and maintenance costs.

In accordance with the invention, a phase-modulation system comprises an input circuit adapted to have applied thereto modulation signals, means for generating reference oscillations, and means for generating comparative oscillations of the mean frequency of the reference oscillations. The system also includes means responsive to the relative phase of corresponding cycles of the reference and comparative oscillations for deriving a control effect, means responsive to the control effect tending to maintain a predetermined constant phase relation.

tion between the reference and comparative oscillations, and means responsive to the modulation signals for modifying the action of the control effect to vary the phase difference between the reference and comparative oscillations from the aforesaid predetermined relation, thereby to phase-modulate the comparative oscillations in accordance with the modulation signals.

In accordance with one form of the invention, a phase-modulation system of the type described comprises means for deriving from one of the reference or comparative oscillation-generating means oscillations of saw-tooth wave form, means for deriving from the other generating means a potential of periodic-pulse wave form having a period and phase corresponding to the oscillations of the said other generating means, and means responsive to the relative phase of the derived potential and the oscillations of saw-tooth wave form for deriving the aforesaid control effect.

In accordance with a particular form of the invention, the phase-modulation system includes a carrier wave source and means responsive to the carrier wave of the source for deriving comparative oscillations of a sub-multiple frequency thereof. Preferably, the aforesaid oscillations of saw-tooth wave form are derived from the reference oscillations and the aforesaid potential of periodic-pulse wave form is derived from the comparative oscillations.

For a better understanding of the present invention, together with other and further objects thereof, reference is had to the following description taken in connection with the accompanying drawings, and its scope will be pointed out in the appended claims.

Referring now to the drawings, Fig. 1 is a circuit diagram, partly schematic, of a complete frequency-modulation transmitter embodying a phase-modulation system in accordance with the present invention; Fig. 2 is a graph used in explaining the operation of the Fig. 1 arrangement; Fig. 3 is a circuit diagram, partly schematic, of a complete frequency-modulation carrier-wave transmitter embodying a modified form of the invention; and Fig. 4 is a graph used as an aid in explaining the operation of the Fig. 3 transmitter arrangement.

Referring now more particularly to Fig. 1, there is represented schematically a complete frequency-modulation carrier-wave transmitter of a conventional design embodying the present invention in a particular form. In general, the transmitter includes a first source of modulation signals, comprising a microphone 10, an audio-frequency amplifier 11 of one or more stages, an integrating system 12, and an audio-frequency amplifier 13 of one or more stages. The modulation-signal source comprising units 10 to 13, inclusive, is coupled to the input circuit 18, 19 of a phase-modulation system 14, more fully described hereinafter. There is coupled to the output circuit of unit 14 one or more frequency-multiplier and radio-frequency amplifier stages 15, and an antenna system 16, 17. The transmitter may also include a second source of modulation signals, comprising a microphone 10', an audio-frequency amplifier 11' of one or more stages, an integrating system 12', and an audio-frequency amplifier 13' of one or more stages which is coupled to a second input circuit comprising input-circuit terminals 18', 19' of the phase-modulation system 14.

It will be understood that the various units just described may, with the exception of the phase-modulation system 14, be of a conventional construction and operation, the details of which are well known in the art, rendering detailed description thereof unnecessary. Considering briefly the operation of the transmitter as a whole, and neglecting for the moment the operation of the phase-modulating system 14, presently to be described, a modulation signal to be transmitted is derived by the microphone 10, is amplified by the audi-frequency amplifier 11, is suitably integrated by the integrating system 12, and after further amplification in the audio-frequency amplifier 13, is applied to an input circuit of the phase-modulation system 14. The phase-modulation system 14 phase-modulates a carrier wave generated therein in accordance with the modulation signals applied to its input-circuit terminals 18, 19 from the modulation-signal source 10, 11, 12, 13 and the phase-modulated carrier wave is applied to the input circuit of unit 15, where its frequency is increased by the frequency-multiplier stages of this unit to a value suitable for radiation by the transmitter. The high-frequency carrier wave is then amplified by the radio-frequency amplifier stage or stages of unit 15 and is applied to the antenna system 16, 17 for radiation.

The modulation signal derived by units 10, 11', 12' and 13' and applied to the second input circuit comprising input-circuit terminals 18', 19' of the phase-modulation system 14 may simultaneously or alternately phase-modulate the carrier wave generated in unit 14, the operation of the transmitter after the phase modulation of the carrier wave being as heretofore described.

Referring now more particularly to the portion of the system embodying the present invention, the phase-modulation system 14 includes an input circuit comprising input-circuit terminals 18, 19 adapted to have applied thereto modulation signals to be transmitted. The system also includes means for generating reference oscillations comprising a piezoelectric crystal-controlled oscillator 20 having a frequency, for example, of 100 kilocycles. There is also included in the system means for generating comparative oscillations of the mean frequency of the reference oscillations comprising an oscillator 21, the frequency of which is determined by an output tuned circuit comprising a condenser 22 and inductor 23.

There is additionally included in the phase-modulation system 14 means responsive to the relative phase of the reference and comparative oscillations, generated by the respective oscillators 20 and 21, for deriving a control effect. This means comprises means for deriving from one of the generating means 20, 21 oscillations of saw-tooth wave form, means for deriving from the other of the generating means 20, 21 a potential of periodic-pulse wave form having a period and phase corresponding to the oscillations thereof, and means responsive to the relative phase of the derived potential and the saw-tooth oscillations for deriving the control effect. In the particular arrangement shown, the means for generating the oscillations of saw-tooth wave form comprises a saw-tooth wave generator 24 having an input circuit coupled to the output circuit of the oscillator 20. The means for generating the potential of periodic wave form comprises a condenser 25 and a resistor 26, the condenser coupling the output circuit of the oscillator 20 to a first control electrode 27 of a vacuum

uum tube 28 and the resistor 26 being connected between the control electrode 27 and the cathode of this vacuum tube. The means responsive to the relative phase of the reference and comparative oscillations for deriving the control effect comprises the vacuum tube 28, which includes a second control electrode 29 coupled through a condenser 30 to the output circuit of the saw-tooth generator 24, and a rectifier device 31 which is coupled through a transformer 32 to the output circuit of the vacuum tube 28. The transformer 32 has a primary winding 33 which is tuned by a condenser 34 to the frequency of the reference oscillations generated by the oscillator 20, the tuned circuit 33, 34 having a pass band sufficiently wide to translate to the rectifier 31 the fundamental frequency and perhaps several harmonic frequencies of pulses derived, in a manner presently to be explained, from the saw-tooth oscillations applied to tube 28 from the generator 24. The rectifier 31 is provided with a load resistor 35 across which there is derived the aforementioned control effect which, as here shown, is a unidirectional control potential. There is connected across the resistor 35 a condenser 36 of such value that the resistor 35 and condenser 36 have a time constant long compared with the period of the lowest frequency of the oscillator 21.

The phase-modulation system 14 additionally includes means responsive to the aforesaid control effect tending to maintain a predetermined constant phase relation between the reference and comparative oscillations. This means comprises a reactance tube 37 having a control electrode 38 coupled through a resistor 39 to the output circuit of the rectifier device 31 and coupled through a condenser 40 to a point on a phasing network comprising a resistor 41 and a condenser 42 which are serially connected across the output tuned circuit 22, 23 of the oscillator 21. The output electrodes of the reactance tube 37 are coupled across the frequency-determining or output tuned circuit 22, 23 of the oscillator 21. As thus arranged, the reactance tube 37 comprises means responsive to the control effect derived across the load resistor 35 of the rectifier device 31 for controlling the frequency of the oscillator 21 and tending to maintain a predetermined constant phase relation between the reference and comparative oscillations generated by the respective oscillators 20 and 21.

The phase-modulation system also includes means responsive to the modulation signals for modifying the action of the aforementioned control effect to vary the phase difference between the reference and comparative oscillations from the aforesaid predetermined relation, thereby to phase-modulate the comparative oscillations of oscillator 21 in accordance with the modulation signals applied to unit 14 from the modulation-signal source 10, 11, 12 and 13. Insofar as the modulation signals derived by this source are concerned, this means comprises a resistor 43 which is coupled across the input-circuit terminals 18, 19 of the phase-modulation system 14 and is included in a series-biasing circuit for the control electrode 28 of the vacuum tube 28, the latter circuit comprising, in addition to the resistor 43, a source of biasing potential $-C$ and a radio-frequency choke coil 44. Insofar as the modulation signals derived by the modulation-signal source 10', 11', 12' and 13' are concerned, the modulation-signal responsive means comprises a resistor 45 coupled across the second pair of input-circuit terminals 18', 19' of the phase-modu-

lating system 14 and included in a series-biasing circuit for the control electrode 38 of the reactance tube 37, the latter circuit comprising a source of bias potential $-C_1$, the resistor 45, the load resistor 35 of rectifier device 31, and the resistor 39.

Considering now the operation of the circuit just described, and referring to the curves of Fig. 2, the reference oscillations generated by the oscillator 20 have a constant frequency since this oscillator is of the piezo-electric crystal-controlled type. The saw-tooth generator 24 derives directly from the reference oscillations saw-tooth oscillations and it will be apparent that the latter are likewise of constant frequency, have a constant phase relation with respect to the reference oscillations, and preferably are of linear saw-tooth wave form, as represented by curve A of Fig. 2. These saw-tooth oscillations are applied through the coupling condenser 30 to the control electrode 29 of the vacuum tube 28. The control electrode 29 is biased to the linear portion of its operating characteristic by the source of biasing potential $-C$. The tube 28, however, is normally biased to cutoff during the major portion of the period of the saw-tooth oscillations by a negative-bias potential developed across the resistor 26 by the action of the control electrode 27 in rectifying the comparative oscillations, represented by the solid-line curve B of Fig. 2 applied thereto through the condenser 25 from the oscillator 21. The control electrode 27 is biased above cutoff e_0 , Fig. 2, only by the positive peaks of the comparative oscillations and thus permits anode current to flow during a relatively short interval t_1-t_2 , t_3-t_4 , etc., of each cycle of the comparative oscillations. The saw-tooth oscillations applied to the control electrode 29 are thus repeated in the output circuit of vacuum tube 28 only during these intervals. The anode current of vacuum tube 28 is consequently of periodic-pulse wave form, as represented by the solid-line curve C of Fig. 2. The output pulses of vacuum tube 28 are peak rectified by the rectifier device 31 to derive across the load resistor 35 a unidirectional control potential. This control potential is applied in series with the biasing potential from the biasing source $-C_1$ to the control electrode 38 of the reactance tube 37 and the biasing potential $-C_1$ is so adjusted that the effective reactance applied across the tuned circuit 22, 23 of the oscillator 21 from the reactance tube 37 is just sufficient to maintain the output pulses of tube 28 at that constant amplitude which corresponds to a predetermined constant phase relation between the reference oscillations of oscillator 20 and the comparative oscillations of oscillator 21. This constant phase relation is preferably such that the positive peaks of the oscillations of oscillator 21 occur at the center point a of the linear portion of the saw-tooth oscillations generated by the saw-tooth generator 24.

It will be evident that, should the phase of the oscillations of oscillator 21 advance with respect to the reference oscillations of oscillator 20, as indicated by the dotted-line curve B', Fig. 2, the periodic-pulse current in the output circuit of vacuum tube 28 has lower amplitude, as represented by the dotted-line curve C'. Hence, the unidirectional potential derived across resistor 35 is smaller than before and the effective reactance of the reactance tube 37 changes in a direction to retard the phase of the comparative oscillations of oscillator 21 in an attempt to restore the

relative phase of the reference and comparative oscillations to the predetermined phase relation initially established. Equilibrium in the phase-correcting action is effected when the comparative and reference oscillations have substantially the predetermined phase initially established. Similarly, should the comparative oscillations of oscillator 21 be delayed in phase with respect to the reference oscillations of oscillator 20, as indicated by the broken-line curve B'' of Fig. 2, the periodic-pulse current in the output circuit of vacuum tube 28 has larger amplitude, as represented by the broken-line curve C'', with resultant increase of the unidirectional potential developed across the resistor 35, thereby to change the effective reactance of the reactance tube 37 to increase the frequency of the comparative oscillations generated by oscillator 21, thus substantially to restore the initial predetermined phase relation between the reference and comparative oscillations.

Assume now that a modulation signal is derived by the modulation-signal source comprising units 10, 11, 12 and 13 and is applied to the input-circuit terminals 18, 19 of the phase-modulation system 14. A modulation signal potential is thus developed across the resistor 43 and is applied to the control electrode 29 of the vacuum tube 28. This has the same effect on the instantaneous potential of the control electrode 29 as though the phase of the saw-tooth oscillations of oscillator 24 were instantaneously advanced or retarded, in accordance with the polarity of the modulation signal, with respect to the comparative oscillations of oscillator 21. The relative phase of the saw-tooth oscillations is advanced or retarded, respectively, by positive and negative values of the modulation signal and the extent of the change in phase varies with the instantaneous amplitude of the modulation signal. The resultant change of the unidirectional control potential developed across the resistor 35 effects a corresponding change in the effective reactance of the reactance tube 37 to cause the comparative oscillations of the oscillator 21 correspondingly to change in phase in such direction that the magnitude of the control potential developed across the resistor 35 is changed toward its initial value. It will be evident, of course, that the magnitude of the unidirectional control potential is not restored to its initial value by the phase change of the comparative oscillations, but rather is changed to such value that an equilibrium value of phase is established between the reference and comparative oscillations. However, since the actual phase of the saw-tooth oscillations of generator 24 has not changed, it will be apparent that the effect of the modulation signal is so to modify the action of the phase-controlling effect or potential developed across the resistor 35 as to vary the phase difference between the reference and comparative oscillations from the predetermined phase relation initially established therebetween, thereby to phase-modulate the comparative oscillations of oscillator 21 in accordance with the modulation signals.

It will be apparent from the above description of the operation of the invention that modulation signals derived by the modulation-signal source comprising units 10', 11', 12' and 13' and applied to the second input-circuit terminals 18', 19' of the phase-modulation system 14 likewise effect a variation of the phase difference be-

tween the reference and comparative oscillations from the predetermined phase relation initially established, thereby to phase-modulate the comparative oscillations in accordance with the modulation signals derived by the microphone 10'. The operation in this respect is essentially similar to that previously described except that the latter modulation signals are directly applied in series with the control potential developed across the load resistor 35 to the control electrode 38 of the reactance tube 37, thus to modify the effect of the control potential in maintaining the initial predetermined phase relation between the reference and comparative oscillations.

While the comparative oscillations of oscillator 21 may thus be simultaneously phase-modulated in accordance with modulation signals applied to both of the pairs of input-circuit terminals 18, 19 and 18', 19' of unit 14, normally only one of the modulation-signal sources comprising units 10 to 13, inclusive, or 10' to 13', inclusive, will be used at any one time, the other source being temporarily deenergized by suitable means or being completely eliminated from the transmitter arrangement.

It will now be evident from the foregoing described operation of the invention that the linearity of wave form of the saw-tooth oscillations generated by unit 24 directly determines the linearity of the phase modulation of the comparative oscillations of oscillator 21. It is relatively easy in accordance with present day practice to obtain saw-tooth oscillations having a high degree of linearity of wave form. Consequently, a transmitter embodying the invention has the advantage that a high degree of linearity of phase modulation of the comparative oscillations may easily be attained. It will further be evident that the phase modulation of the comparative oscillations may extend over a relatively wide range equal to a phase deviation of ± 170 degrees with respect to the reference oscillations of oscillator 20 if 20 degrees of the saw-tooth oscillation are allowed for the retrace portion thereof and a reasonable value is allowed for the duration of the pulses of the periodic potential derived from the comparative oscillations of oscillator 21. This has the advantage that fewer frequency-multiplier stages are required in unit 15 of the transmitter to obtain the high-frequency frequency-modulated carrier wave desired for radiation. For example, it can be shown that:

$$\phi_{\max} = \frac{\Delta f_{\max}}{f_a} \quad (1)$$

where

$\phi_{\max}$ =the maximum phase deviation corresponding to the maximum frequency deviation desired,

$\Delta f_{\max}$ =the maximum frequency deviation desired, and

f_a =the lowest-frequency component of the modulation signal.

Thus, if the comparative oscillations are phase-modulated over a range of ± 3 radians, which corresponds approximately to ± 170 degrees, and it is desired that the maximum frequency deviation be ± 75 kilocycles and the lowest-frequency component of the modulation signal is 30 cycles, it will be seen from Equation 1 that the maximum phase deviation is ± 2500 radians and the necessary frequency multiplication of the modulated carrier wave must then be 833 times. In contrast to this, frequency multiplication of the

order of 5000 times has been required in the prior art phase-modulation systems for the same maximum frequency deviation and the same value of low-frequency component of the modulation signal, since phase modulation of the low-frequency oscillations in such systems could only be effected over approximately plus or minus one-half radian thereof if any semblance of linearity of phase modulation was to be retained.

Fig. 3 represents a modified form of phase-modulation system of the invention which is essentially similar to that of Fig. 1, similar circuit elements being designated by similar reference numerals and analogous circuit elements by similar reference numerals primed, except that a modified form of phase-modulation control is employed in the instant arrangement and fewer frequency-multiplication stages are required to produce the high-frequency frequency-modulated wave to be radiated. The phase-modulation control system in this arrangement comprises a pair of control vacuum tubes 28, 28' having a pair of rectifier devices 31, 31' individually coupled to the output circuits thereof. Each of the rectifier devices 31, 31' has an output load impedance comprising respective load resistors 35, 35' and respective parallel-connected condensers 36, 36', the load resistors 35 and 35' being serially included in the biasing circuit of the control electrode 38 of the reactance tube 37. The saw-tooth wave generator 24' develops balanced saw-tooth oscillations in its output circuit, which oscillations are applied with one phase through the condenser 30 to the control electrode 29' of vacuum tube 28' and with opposite phase through a condenser 30' to the control electrode 29 of vacuum tube 28. The modulation signals applied to the input-circuit terminals 18, 19 of the phase-modulation system 14' are applied through a modulation transformer 46 with opposite phase to the control electrodes 29 and 29' of the respective vacuum tubes 28 and 28'.

Also in the arrangement of Fig. 3, the oscillator 21' comprises a carrier-wave source, the resonant circuit 22', 23' thereof being tuned to a frequency higher than that of the reference oscillator 20. There is included means responsive to the carrier wave generated by the oscillator 21' for deriving comparative oscillations of a submultiple frequency thereof, the mean frequency of the comparative oscillations being equal to the frequency of the reference oscillations of oscillator 20. This means is essentially a frequency divider and comprises a vacuum tube 47 having a control electrode 48 connected to ground through a grid-leak resistor 49 and coupled through a condenser 50 to the output circuit of the carrier-wave oscillator 21'. The output circuit of the vacuum tube 47 comprises a transformer winding 53 which is tuned by a condenser 54 to one-fourth of the mean frequency of the carrier wave applied to the input circuit of vacuum tube 47. A transformer winding 55 is coupled to the winding 53 and is connected to a control electrode 56 of a vacuum tube 57. The output circuit of the vacuum tube 57 comprises a primary winding 58 of a transformer 59, the secondary winding 60 of which is tuned by a condenser 61 to three-fourths of the mean frequency of the carrier wave generated by oscillator 21'. The transformer secondary winding 60 is coupled to a second control electrode 62 of vacuum tube 47. A tertiary transformer winding 63 is coupled to the winding 53 included in

the output circuit of vacuum tube 47 and is coupled through the condenser 25 to the control electrode 27 of vacuum tube 28 and to a corresponding control electrode 27' of vacuum tube 28'.

Considering now the operation of the circuit just described, and referring to the curves of Fig. 4, the saw-tooth oscillations generated by unit 24' and applied to the control electrode 29 of vacuum tube 28 are represented by the solid-line curve D, while the saw-tooth oscillations applied to the control electrode 29' of vacuum tube 28' are represented by the broken-line curve E. The carrier wave generated by the carrier-wave oscillator 21' has, in the arrangement described, a mean frequency four times that of the reference oscillations generated by oscillator 20. There is derived from this carrier wave by the frequency-divider stage comprising vacuum tubes 47 and 57 comparative oscillations of a submultiple frequency of the carrier wave and having a mean frequency equal to that of the reference oscillations. These comparative oscillations are applied through the transformer winding 63 and through the condenser 25 in like phase to the control electrodes 27 and 27' of the respective vacuum tubes 28 and 28'. As in Fig. 1, the control electrodes 27 and 27' rectify the comparative oscillations to derive across the resistor 26 a bias potential sufficiently large that the vacuum tubes 28, 28' are conductive only during a relatively short interval of each positive peak of the comparative oscillations when the control electrodes are instantaneously biased above their cut-off bias e_0 , as indicated by the portion of the solid-line curve F of Fig. 4. Consequently, the saw-tooth oscillations applied to the control electrodes 29 and 29' of the respective vacuum tubes 28 and 28' are repeated in the output circuits of these tubes only during the relatively short intervals when the tubes are conductive.

Assuming that the reference and comparative oscillations have the relative phase indicated in Fig. 4, the periodic current in the output circuit of tube 28, which current may have a wave form as represented by the portion of the solid-line curve G above the axis O—O, is peak rectified by the rectifier device 31 to develop across the load resistor 35 a first unidirectional potential. Similarly, the current in the output circuit of tube 28' is of periodic-pulse wave form, as represented by the solid-line curve G below the axis O—O, and there is derived across the load resistor 35' a second unidirectional control potential of polarity opposite to that of the first unidirectional control potential. When the reference and comparative oscillations applied to the vacuum tubes 28 and 28' have the phase relation indicated in Fig. 4, the unidirectional control potentials derived across the resistors 35 and 35' are equal and thus exactly oppose each other in the biasing circuit of the control electrode 38 of the reactance tube 37. The bias $-C_1$ is initially so adjusted as in the arrangement of Fig. 1 that the reference and comparative oscillations have a desired predetermined phase relationship under the conditions just assumed.

Now should the frequency of the carrier wave generated by the oscillator 21' change, the phase of the comparative oscillations produced by the frequency divider comprising tubes 47 and 57 correspondingly changes, though to a lesser degree due to the frequency division, with respect to the reference oscillations of oscillator 20.

Thus, if the comparative oscillations have advanced phase with respect to the reference oscillations, as represented by the broken-line curve F' of Fig. 4, the output of the vacuum tube 28 is reduced, as indicated by the portion of the dotted-line curve G' extending above the axis 0-0, while the output of the vacuum tube 28' increases, as represented by the dotted-line curve G' below the axis 0-0. Consequently, the unidirectional control potential developed across the resistor 35' is larger than that developed across the resistor 35 with the result that a control bias is applied to the control electrode 38 of the reactance tube 37 to cause a change of the effective reactance of the latter in a direction to change the frequency of the carrier-wave oscillator 21' in an attempt to restore equality of the unidirectional potentials derived across the resistors 35 and 35'. As previously pointed out, however, sufficient inequality of the unidirectional potentials is required to effect a state of equilibrium between the phase of the reference and comparative oscillations. In this connection, it may be noted that the reactance tube 37 must cause a phase shift of the carrier-wave oscillations of oscillator 21' four times as large as that required of the comparative oscillations to effect the desired balance of outputs of the rectifier devices 31 and 31'. The arrangement of Fig. 3 thus produces a large phase shift of the carrier-wave oscillations generated by oscillator 21' for relatively small phase differences between the reference and comparative oscillations.

It will be evident that, should the phase of the comparative oscillations be retarded with respect to the reference oscillations, as indicated by the broken-line curve F'' of Fig. 4, the output of the vacuum tube 28 is now increased and that of vacuum tube 28' decreased, as represented by the portions of the broken-line curve H respectively above and below the axis 0-0. The resultant of the control potentials now developed across the resistors 35 and 35' has a polarity opposite to that previously described and which resulted from an advance in phase of the comparative oscillations with respect to the reference oscillations. The phase correction applied to the carrier-wave oscillator 21' by the reactance tube 37 is thus opposite to that previously described and again effects substantial equality of outputs of the rectifiers 31 and 31'.

The effect of the modulation signals applied to the input circuit terminals 18, 19 of unit 14' in the Fig. 3 arrangement is similar to that described in connection with Fig. 1 in that it has the same effect as though the saw-tooth oscillations applied to the control electrodes 28 and 29' of the respective vacuum tubes 28 and 28' were changed in phase, though there is the difference that the modulation signals have the effect of advancing the phase of the saw-tooth oscillations applied to one of the tubes, for example the tube 28, and of retarding the phase of the saw-tooth oscillations applied to the other, for example the tube 28', thus producing an unbalance of the outputs of the rectifier devices 31 and 31' of the same type as though the comparative oscillations had changed in phase with respect to the reference oscillations. The operation of the Fig. 3 arrangement is otherwise essentially similar to that of Fig. 1 and will not be repeated.

The arrangement of Fig. 3 has the advantage that the phase of the carrier-wave oscillations of oscillator 21' is varied over a wider phase

range by a modulation signal of given amplitude than is the case in the arrangement of Fig. 1. The Fig. 3 modification thus requires fewer stages of frequency multiplication in unit 15 of the transmitter to produce the required high-frequency frequency-modulated carrier wave for radiation.

It will be apparent from the foregoing description that the mean fundamental frequencies of the reference and comparative operations are integrally related. In the Fig. 1 embodiment, for example, these oscillations have the same mean fundamental frequency. It will also be apparent that a phase-modulation system in accordance with the invention comprises means responsive to the timing of corresponding cycles of the reference and comparative oscillations which have the same mean time separation for deriving a control effect. As used here, the term "corresponding" is intended to designate a correspondence in time. Referring again to the Fig. 1 embodiment, this means comprises vacuum tube 28, diode 31, and their associated circuits. Where, as in the embodiment under consideration, the reference and comparative oscillations have the same mean fundamental frequency, succeeding cycles of the reference oscillations have the same mean time separation as succeeding cycles of the comparative oscillations so that the means comprised of vacuum tube 28 and diode 31 are responsive to corresponding and successive cycles of the reference and comparative oscillations, as illustrated by the curves of Fig. 2. Expressed in other words, the described means are responsive to the relative phase of the reference and comparative oscillations for the stated operating condition and the derived control effect is utilized to maintain a predetermined constant timing or phase relation between corresponding cycles of the reference and comparative oscillations.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A phase-modulation system comprising, an input circuit adapted to have applied thereto modulation signals, means for generating reference oscillations, means for generating comparative oscillations of the mean frequency of said reference oscillations, means responsive to the relative phase of corresponding cycles of the reference and comparative oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

2. A phase-modulation system comprising, an input circuit adapted to have applied thereto modulation signals, means for generating reference oscillations of substantially constant frequency, means for generating comparative oscillations

lations of the mean frequency of said reference oscillations, means responsive to the relative phase of corresponding cycles of the reference and comparative oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

3. A phase-modulation system comprising, an input circuit adapted to have applied thereto modulation signals, means for generating reference oscillations, means for generating comparative oscillations of the mean frequency of said reference oscillations, means for deriving from one of said generating means oscillations of saw-tooth wave form, means responsive to the relative phase of the oscillations of the other of said generating means and said saw-tooth oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

4. A phase-modulation system comprising, an input circuit adapted to have applied thereto modulation signals, means for generating reference oscillations, means for generating comparative oscillations of the mean frequency of said reference oscillations, means for deriving from one of said generating means oscillations of linear saw-tooth wave form, means responsive to the relative phase of the oscillations of the other of said generating means and said saw-tooth oscillations for deriving a control effect varying linearly therewith, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby linearly to phase-modulate said comparative oscillations in accordance with said modulation signals.

5. A phase-modulation system comprising, an input circuit adapted to have applied thereto modulation signals, means for generating reference oscillations, means for generating comparative oscillations of the mean frequency of said reference oscillations, means responsive to the relative phase of corresponding cycles of the reference and comparative oscillations for deriving a unidirectional control potential, means responsive to said control potential tending to maintain a predetermined constant phase relation between said reference and comparative oscillations, and means responsive to said modulation signals for modifying the action of said unidirectional control potential to vary the phase difference between said reference and comparative oscillations from said predetermined relation, thereby to phase-modulate said comparative os-

cillations in accordance with said modulation signals.

6. A phase-modulation system comprising, an input circuit adapted to have applied thereto modulation signals, means for generating reference oscillations, means for generating comparative oscillations of the mean frequency of said reference oscillations, means responsive to the relative phase of corresponding cycles of the reference and comparative oscillations for deriving a unidirectional control potential having an amplitude varying with said relative phase, means responsive to said control potential tending to maintain a predetermined constant phase relation between said reference and comparative oscillations, and means responsive to said modulation signals for modifying the action of said control potential to vary the phase difference between said reference and comparative oscillations from said predetermined relation, thereby to phase-modulate said comparative oscillations in accordance with said modulation signals.

7. A phase-modulation system comprising, an input circuit adapted to have applied thereto modulation signals, means for generating reference oscillations, means for generating comparative oscillations of the mean frequency of said reference oscillations, means for deriving from the oscillations of one of said generating means a potential of periodic-pulse wave form having a period and phase corresponding to the oscillations of said one generating means, means responsive to the relative phase of said derived potential and the oscillations of the other of said generating means for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

8. A phase-modulation system comprising, an input circuit adapted to have applied thereto modulation signals, means for generating reference oscillations, means for generating comparative oscillations of the mean frequency of said reference oscillations, means for deriving from the oscillations of one of said generating means a potential of periodic-pulse wave form having substantially constant amplitude and having a period and phase corresponding to the oscillations of said one generating means, means for generating from the oscillations of the other of said generating means oscillations of saw-tooth wave form, means responsive to the relative phase of said derived potential and said saw-tooth oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

9. A phase-modulation system comprising, an input circuit adapted to have applied thereto modulation signals, means for generating reference oscillations, means for generating compara-

tive oscillations of the mean frequency of said reference oscillations, means responsive to said comparative oscillations for deriving a potential of periodic-pulse wave form having a period and phase corresponding to said comparative oscillations, means responsive to said reference oscillations for deriving oscillations of saw-tooth wave form having the same period as said reference oscillations, means responsive to the relative phase of said derived potential and said saw-tooth oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

10. A phase-modulation system comprising, an input circuit adapted to have applied thereto modulation signals, means for generating reference oscillations, means for generating comparative oscillations of the mean frequency of said reference oscillations, vacuum-tube means responsive to the relative phase of corresponding cycles of the reference and comparative oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

11. A phase-modulation system comprising, an input circuit adapted to have applied thereto modulation signals, means for generating reference oscillations, means for generating comparative oscillations of the mean frequency of said reference oscillations, means including a vacuum tube having two control electrodes individually coupled to said first-named and second-named generating means for deriving a control effect varying in magnitude with the relative phase of corresponding cycles of said reference and comparative oscillations, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

12. A phase-modulation system comprising, an input circuit adapted to have applied thereto modulation signals, means for generating reference oscillations, means for generating comparative oscillations of the mean frequency of said reference oscillations, means for deriving from the oscillations of one of said generating means oscillations of saw-tooth wave form having the same period as the oscillations of said one generating means, means for deriving from the oscillations of the other of said generating means a potential of periodic-pulse wave form having the same period as the oscillations of said other gener-

ating means, means including a vacuum tube having a pair of control electrodes individually coupled to said first-named and second-named deriving means for deriving a control effect varying in magnitude with the relative phase of said derived potential and said saw-tooth oscillations, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

13. A phase-modulation system comprising, an input circuit adapted to have applied thereto modulation signals, means for generating reference oscillations, means for generating comparative oscillations of the mean frequency of said reference oscillations, means for translating the oscillations of one of said generating means only during a fixed and relatively short interval of each cycle of the oscillations of the other of said generating means, means responsive to said translated oscillations for deriving a control effect, means responsive to said control effect tending to maintain a predetermined constant phase relation between said reference and comparative oscillations, and means responsive to said modulation signals for modifying the action of said control effect to vary the phase difference between said reference and comparative oscillations from said predetermined relation, thereby to phase-modulate said comparative oscillations in accordance with said modulation signals.

14. A phase-modulation system comprising, an input circuit adapted to have applied thereto modulation signals, means for generating reference oscillations, means including an oscillator for generating comparative oscillations of the mean frequency of said reference oscillations, means responsive to the relative phase of corresponding cycles of the reference and comparative oscillations for deriving a control effect, means responsive to said control effect for controlling the frequency of said oscillator to tend to maintain a predetermined constant phase relation between said reference and comparative oscillations, and means responsive to said modulation signals for modifying the action of said control effect in controlling the frequency of said oscillator to vary the phase difference between said reference and comparative oscillations from said predetermined relation, thereby to phase-modulate said comparative oscillations in accordance with said modulation signals.

15. A phase-modulation system comprising, an input circuit adapted to have applied thereto modulation signals, a carrier-wave source, means responsive to the carrier wave of said source for deriving comparative oscillations of a submultiple frequency thereof, a source of reference oscillations having a frequency equal to the mean frequency of said comparative oscillations, means responsive to the relative phase of corresponding cycles of said reference and comparative oscillations for deriving a control effect, means responsive to said control effect for controlling the frequency of said carrier wave to tend to maintain a predetermined constant phase relation between said reference and comparative oscillations, and means responsive to said modulation signals for modifying the action of said control

effect in controlling the frequency of said carrier wave to vary the phase difference between said reference and comparative oscillations from said predetermined relation, thereby to phase-modulate said carrier wave in accordance with said modulation signals.

16. A phase-modulation system comprising, an input circuit adapted to have applied thereto modulation signals, a carrier-wave source, means responsive to the carrier wave of said source for deriving comparative oscillations of a submultiple frequency thereof, a source of reference oscillations of saw-tooth wave form having a frequency equal to the mean frequency of said comparative oscillations, means for deriving from said comparative oscillations a unidirectional potential of periodic-pulse wave form having a period equal to that of said comparative oscillations, means responsive to the relative phase of said derived potential and said saw-tooth oscillations for deriving a control effect, means responsive to said control effect for controlling the frequency of said carrier wave to tend to maintain a predetermined constant phase relation between said reference and comparative oscillations, and means responsive to said modulation signals for modifying the action of said control effect in controlling the frequency of said carrier wave to vary the phase difference between said reference and comparative oscillations from said predetermined relation, thereby to phase-modulate said carrier wave in accordance with said modulation signals.

17. A phase-modulation system comprising, an input circuit adapted to have applied thereto modulation signals, means for generating reference oscillations, means for generating comparative oscillations, the mean fundamental frequencies of said reference and comparative oscillations being integrally related, means responsive to the timing of corresponding cycles of said reference and comparative oscillations which have the same mean time separation for deriving a control effect, means responsive to said control effect tending to maintain a predetermined constant timing between said corresponding cycles of said reference and comparative oscillations, and means responsive to said modulation signals for modifying the action of said control effect to vary the timing between said reference and comparative oscillations from said predetermined timing,

thereby to phase-modulate said comparative oscillations in accordance with said modulation signals.

18. A phase-modulation system comprising, an input circuit adapted to have applied thereto modulation signals, means for generating reference oscillations of substantially constant frequency, means for generating comparative oscillations having a mean fundamental frequency integrally related to the frequency of said reference oscillations, means responsive to the timing of corresponding cycles of said reference and comparative oscillations which have the same mean time separation for deriving a control effect, means responsive to said control effect tending to maintain a predetermined constant timing between said corresponding cycles of said reference and comparative oscillations, and means responsive to said modulation signals for modifying the action of said control effect to vary the timing between said reference and comparative oscillations from said predetermined timing, thereby to phase-modulate said comparative oscillations in accordance with said modulation signals.

19. A phase-modulation system comprising, an input circuit adapted to have applied thereto modulation signals, means for generating reference oscillations, means for generating comparative oscillations, the mean fundamental frequencies of said reference and comparative oscillations being integrally related, means for deriving from the oscillations of one of said generating means pulses of potential having a period and phase corresponding to the oscillations of said one generating means, means responsive to the timing of said pulses and corresponding cycles of the oscillations of the other of said generating means which have the same mean time separation for deriving a control effect, means responsive to said control effect tending to maintain a predetermined constant timing between corresponding cycles of said reference and comparative oscillations, and means responsive to said modulation signals for modifying the action of said control effect to vary the timing between said reference and comparative oscillations from said predetermined timing, thereby to phase-modulate said comparative oscillations in accordance with said modulation signals.
